**METHOD OF AND MEANS FOR CASTING METALS
UNDER THE INFLUENCE OF VACUUM**

William G. Wilkins, Chicago, Ill., assignor to Universal Castings Corporation, Chicago, Ill., a corporation of Illinois

Application March 3, 1958, Serial No. 719,182

5 Claims. (Cl. 22—73)

The present invention relates generally to casting, especially of metals, and more particularly to a new and improved method of casting and apparatus by means of which the method can be practiced.

The invention finds particular, though by no means exclusive, utility in precision casting as is frequently employed in forming devices embodying cored openings of arcuate or irregular shape, those having extremely thin-walled portions, and those from which no substantial metal removal by machining is to be subsequently effected. In conventional practice the material to be cast is first heated to a temperature well above its melting point and is introduced into a mold by way of a sprue opening which is connected to the mold cavity by way of a runner, provision being made to vent the mold cavity and to incorporate risers and shrinkheads to insure filling of the cavity and by providing additional metal to compensate for shrinkage during cooling. By way of example, in the casting of aluminum the temperature is initially raised to approximately 1600° F. so as to obtain desired fluidity. This extremely high temperature has been found necessary in conventional practice where castings having thin-walled sections are to be made. In the casting of such devices by conventional methods only about one-third of the metal poured is utilized to form the casting per se, the remainder going into the runners, risers, shrinkheads, and sprue openings. Furthermore, under conventional practice at extremely high temperatures required, it has been found that up to 70% of the castings so formed had to be scrapped because of incomplete filling of the mold cavities and because of high porosity which results in poor physical properties, primarily with regard to tensile strength. Investigations have led to the belief that as a result of the requisite high temperature required to obtain the required fluidity, there is a substantial increase both in the occlusion of gases and in oxide formation. X-ray pictures indicate such porosity as literally hundreds of interstices of voids. Further, the incomplete formation of the edges of remote portions of castings made under conventional practice is believed to be caused by the incomplete removal of air and other gases from remote portions of the mold cavity.

Accordingly, it is a general object of the present invention to provide an improved method of casting by means of which the above-mentioned difficulties are substantially eliminated. It is a related object to provide a method of casting metals permitting of more rapid and economical practice, and whereby the initial temperature to which the metal to be cast need be raised is only slightly above its melting point so as to achieve the attendant advantages of decreasing oxidation and the entrainment of oxides within the castings, and of decreasing gas occlusion, to the end that castings having improved physical properties obtain.

It is another object of the invention to provide a method of casting metals whereby complete removal of air and other gases from the mold cavity is effected and complete filling of the mold cavity with the molten cast-

2

ing material is insured to the end that completely formed castings are obtained.

Another and equally important object of the invention is to provide apparatus by means of which the new and improved method of casting can be practiced for producing ferrous as well as non-ferrous metal castings.

The objects of the invention thus generally set forth, together with other objects and ancillary advantages, will become apparent as the following description proceeds taken in conjunction with the accompanying drawings, in which:

Figure 1 is an elevation of a casting apparatus embodying features of the present invention and by means of which the novel method can be practiced.

Fig. 2 is a top plan view of the apparatus shown in Fig. 1.

Fig. 3 is a vertical section taken in offset planes along the line 3—3 in Fig. 2.

Fig. 4 is a bottom plan view of the top plate of the apparatus shown in the preceding figures.

Fig. 5 is a bottom plan view of a typical top mold section.

Figs. 6 and 7 are perspective views of castings of complex form which have been successfully made through the practice of the instant invention.

Figs. 8 and 9 are central vertical sections taken through a casting like that shown in Fig. 7, the former being made by conventional practice and the latter according to the present invention. These figures comprise reproductions of actual photomicrographs.

Figs. 10 and 11 are vertical sectional views similar to Fig. 3 but illustrating modified forms of apparatus embodying features of the present invention.

Figs. 12 and 13 are elevation and plan views, respectively, of a further modified form of the apparatus as employed in casting metals having an extremely high melting point, such as ferrous metals.

Figs. 14 and 15 are elevation and plan views, respectively, of yet another modified form of apparatus embodying features of the present invention.

Fig. 16 is a bottom plan view of the vacuum plate shown in Figs. 12, 13, 14 and 15.

Fig. 17 is an enlarged vertical sectional view along the line 17—17 in Fig. 12.

Fig. 18 is a fragmentary perspective view looking upwardly at the underside of a modified form of clamping plate (porous disc not shown) also embodying features of the present invention.

Fig. 19 is a fragmentary bottom plan view of the modified form of clamping plate shown in Fig. 18.

Fig. 20 is an enlarged vertical sectional view taken along the line 20—20 in Fig. 19, with the porous disc shown in elevation.

While the invention is susceptible of various modifications and alternative constructions, there are shown in the drawings and will herein be described in detail certain preferred embodiments, but it is to be understood that is not thereby intended to limit the invention to the specific forms disclosed, but it is intended to cover all modifications and alternative constructions falling within the spirit and scope of the invention as expressed in the appended claims.

Referring more particularly to the drawings there is shown a casting apparatus embodying features of the present invention which comprises generally a mold 20, including an upper section 20a and a lower section 20b, mounted between a bottom supporting plate 22 and a top clamping plate 24. As shown, the two mold sections are arranged to meet in a flat parting plane as indicated at 25, and may be equipped with positioning dowels 26 (Figs. 3 and 5). The mold sections have formed in their contiguous faces appropriate recesses which define

one or more mold cavities 28. These cavities are connected by a runner 30 to a sprue opening 32 through which the molten material to be cast is introduced into the mold 20.

The bottom plate 22 of the apparatus may be permanently attached to any suitable supporting structure, as for example an I-beam 34. The upper plate is suitably ribbed as at 36 to provide adequate strength, and is equipped with a spider 38 which is adapted for connection as at 39 to any suitable means (not shown) for raising and lowering the upper plate into and out of engagement with the top mold section 20a. The top plate has a collared opening 40 therein which is adapted to receive an annular ceramic insert 42 and hold same in registry with the sprue opening 32 in the top mold section 20a whereby to direct the molten material to be cast from a ladle or the like (not shown) into the mold 20.

To direct a ladle or the like into proper position for pouring its contents into the open end of the ceramic insert 42 in the top plate 24, a V-shaped guide 44 is provided. The guide, as shown, is formed of ordinary angle-iron sections 44a held in rigid relation by means of a cross strip 44b welded thereto. The guide 44 is mounted on the top plate 24 over the spider 38, in such a position that its legs extend outwardly to include therebetween the collared top plate opening 40.

The present invention contemplates casting under the influence of vacuum indirectly applied to the mold cavity. This is to the end that air and other gases are positively removed from the cavity and the molten material to be cast is drawn from the sprue opening and runner into the cavity against the walls thereof even in the most remote regions of the cavity. More particularly, it is contemplated that evacuation of the mold cavity is to be effected through the walls of the mold that define the cavity. Thus there is a complete removal of air and the like from the cavity and a drawing of the material being cast directly against the cavity walls where it is held until solidification. It will be seen, therefore, that the cavity is quickly filled and complete filling is assured with the result that the necessary initial temperature of the casting material need be only slightly above the melting point thereof. Further, completely formed castings are produced even in such far reaches of a complex cavity as define knife-thin cast sections. As a result of the lower casting temperature porosity is minimized and shrinkage is substantially reduced. These things both contribute markedly to a high yield percentage of good sound castings for the quantity of casting material poured.

In carrying out the invention molds formed of porous ceramic material are utilized and the cavities therein are subjected to an indirectly applied vacuum. That is to say, vacuum is applied exteriorly of the mold, and the cavities therein are evacuated through the walls thereof by virtue of the porous character of the material of which the mold sections are formed. This positively and completely evacuates the mold cavity, eliminates the time and necessity for air or the like trapped in remote regions thereof to be absorbed by the mold, and the molten material introduced into the cavity is drawn quickly against the walls thereof.

In the form of the invention illustrated in Figs. 1-5, inclusive, of the drawings, the mold 20 is formed of a porous ceramic material such as molder's plaster. One suitable form of such plaster comprises the following ingredients substantially in the following proportions by weight:

	Percent
Calcium sulphate	70
Magnesium silicate	27
Terra alba and sugar	3

For use the plaster is mixed with water in adequate amount to obtain the desired molding consistency. This plaster will set in a comparatively short time and is in-

hibited against cracking. Subsequent to the setting of the plaster, green mold sections 20a and 20b are removed from their molding boxes and are heated in a suitable oven to a suitable temperature for a sufficient time to cure them and to remove a cavity forming material if such was used.

The mold sections 20a and 20b, thus formed, are then placed in superimposed relation on the bottom supporting plate 22 and the top plate 24 is lowered into clamping engagement therewith.

In the present instance, the cavities 28 of the mold 20 are evacuated by subjecting the mold to a vacuum applied to the top surface of the mold section 20a so as to withdraw air and other gases from the cavities 28 and to draw the molten material being cast against the cavity walls. As shown, the top plate 24 is formed with a waffle-iron-like lower surface 45 so as to define a pattern of interconnected passages 46 over substantially the entire upper surface of the upper mold section 20a. To provide communication between these interconnected passages and a vacuum pump, the top plate is provided with an opening 47 which is suitably adapted for the reception of a fitting 48 for accommodating a vacuum hose 49.

The waffle-iron-like formation of the underside of the top plate 24 is preferable to a single uniform cavity formation, which might be used, because the top plate serves not only as the medium for the application of vacuum to the mold 20, but additionally through the operation of the clamping means, including the spider 38, to apply a clamping force to the mold 20 so as to maintain the top and bottom mold sections 20a and 20b, respectively, in intimate engagement. The waffle-iron-like formation provides feet or pads 50 distributed over the entire top surface of the top mold section 20a so as to uniformly apply the clamping pressure thereto. Thus, the mold sections 20a and 20b are firmly held together so as to minimize leakage into the mold cavities 28 between the mold sections 20a and 20b along the parting plane 25.

To further insure the application of vacuum to the mold cavities 28 and to further minimize leakage top plate 24 is equipped with suitable knife edges which are adapted to bite into the relatively soft upper surface of the top mold section 20a. Thus, adjacent the marginal edges of the underside thereof, the top plate 24 is suitably grooved for the reception of knife-edged inserts 51. The inserts are suitably sized for press-fitting into the grooved undersurface of top plate 24 and project downwardly therefrom. Similarly an annular knife-edged insert 52 is provided about the collared opening 40. This construction assures inflow of air and other gases into the interconnected passages 46 on the underside of the top plate only by way of the porous walls of the mold 20. This particular construction is advantageous, too, in that it readily permits replacement of the knife-edged inserts 51 and 52 if they should become dull or damaged.

From the foregoing it will be seen that when molten metal or other material is poured into the funnelled open end of the ceramic liner 42 which is received within the collared opening 40 in the top clamping plate 24 and into the sprue opening 32 in the top mold section 20a, it is immediately drawn along the runner 30 into the mold cavities 28 and against the walls of the latter by the vacuum indirectly applied thereto to the top mold section 20a.

In Figs. 6-9, inclusive, there are shown two forms of impellers, generally denoted 60 and 62, as illustrative of the type of complex precision cast products which have been successfully made by the practice of the present invention. Both of these devices are of a form making it practically impossible for subsequent metal removal of machining. Nevertheless, these devices must be precision made because they are intended for rotation at extremely high speeds thereby requiring that they be

dynamically balanced. Figures 8 and 9 are central longitudinal sections taken through impellers of the type shown in Fig. 7, and comprise reproductions of actual photomicrographs. The impeller section shown in Fig. 8 was made by conventional practice wherein the aluminum alloy of which the device was fabricated was heated to an initial temperature of substantially 1600° F. introduced into a mold and permitted to cool. The section shown in Fig. 9 was made by the practice of the present invention and with aluminum alloy from the same original melt but heated to an initial temperature of only 1275° F. and introduced into apparatus such as that herein before described and shown in Figs. 1-5. The relatively high porous character of the casting section shown in Fig. 8 is at once apparent. In Fig. 9, however, the casting section there shown is homogeneous and substantially free of voids.

In Fig. 10 there is shown a slightly modified form of the apparatus embodying features of the present invention. Where practical, identical reference characters have been utilized in the description of these modified forms as have been utilized in connection with the form of the invention shown in Figs. 1-5, inclusive. In this device the mold 20 comprising the mold sections 20a and 20b and the top clamping plate 24 are identical with the preceding form. In this form, however, not only is a vacuum indirectly applied to the mold cavities 28 by directly applying the same to the top surface of the upper mold section 20a, but in addition a vacuum is applied uniformly over the bottom surface of the 30 bottom mold section 20b. Thus the device shown in Fig. 10 is equipped with a bottom supporting plate 26A which, like the top plate 24, has the upper surface thereof, which is engageable with the mold 20, made of waffle-iron-like form so as to provide a pattern of interconnected spaces or passages 66 and suitable supporting pads 68. The bottom plate 26A is equipped with a suitable vacuum hose connection 70 which communicates with the system of passages 66 by way of a port 71 formed in the bottom plate 26A in the outer end of 40 which the hose connection 70 is received. This form of the invention tends to more quickly exhaust the mold cavities 28 and to draw the metal from the sprue opening 32 runner 30 and mold cavities 28 at a somewhat greater rate. It will be appreciated of course that shortly after the molten material to be cast is introduced into the mold the lowermost surfaces of the mold cavities, the sprue opening 32 and the runner 30 are covered by the molten material which substantially closes off the outflow of air therefrom. This construction, however, reduces the time required to fill the mold completely by a substantial amount. Not only is the mold evacuated more quickly by way of the top section 20a and, initially, in conjunction with the evacuation by way of the bottom plate, but several additional advantages come about by this construction. Among the advantages is the fact that both mold sections 20a are held firmly against the contiguous plates thereby permitting of ready separation of the two mold sections by the action of atmospheric pressure on the adjacent sides of the sections as a result of evacuating the spaces behind the same. Of course, since the molten material to be cast covers the lowermost interior surfaces of the mold cavities 28 and the runner 30, the vacuum indirectly applied to the bottom mold section 20b has relatively little effect on the further evacuation of the mold cavities because the pores of the material of which the lower mold section is formed are in effect sealed off by the molten material. However, some evacuation is had by way of the interconnected pores around these surfaces. Thus, the "hold-down" action on the bottom mold section and the additional exhaust of the interior of the mold makes this construction not only practical but desirable as well.

The form of the invention shown in Fig. 11 includes 75

a mold 20B comprising upper and lower mold sections defining mold cavities 28B disposed between a top clamping plate 24B and a lower supporting plate 26B. In this form of the invention, however, the molten material to be cast is introduced in the interior of the mold 20B by way of a sprue opening 32B formed in the lower section of the mold 20B which is in registry with an opening 75 formed in the supporting plate 26B, the latter being lined with a suitable ceramic insert 76. 10 The mold cavities 28B are connected with the opening 75 in the bottom section of the mold 20B by way of a runner 30B.

In this instance it is intended that the molten material to be cast be drawn upwardly through the opening 76 in the supporting plate 26B and in the bottom section of the mold 20B and thence by way of the runner 30B into the mold cavities 28B by means of vacuum indirectly applied to the top section of the mold 20B. Thus the clamping plate 24B is also waffle-iron-like 15 form, providing a pattern of interconnected passages 79 which serve to apply a vacuum substantially uniformly over the upper surface of the top section of the mold 20B. The passages 79 are connected to suitable evacuation apparatus (not shown) by way of an opening 80 20 formed in the clamping plate 24B which is adapted to receive a vacuum hose connection 81.

While in the illustrative embodiments molds of general rectangular figuration have been shown for purposes of illustration, it will be readily appreciated that molds may be made of any desired shape—square, rectangular, oval, etc.—and the upper and lower clamping plates in such cases will be fashioned to conform thereto. In each instance, along the outer marginal edges of the clamping and supporting plates and about 35 the sprue openings in the molds there is provided a sharp depending flange or knife-edge 51B and 52B adapted to bite quite deeply into the contiguous mold surfaces so that when the mold is clamped therebetween a tight seal is provided between the contiguous plate and mold surfaces thereby insuring that the inflowing air into the plate passages is effected by way of the pores of the mold section. In this way, with the plates so designed that vacuum is applied substantially uniformly over the entire contiguous mold section surface, the mold designer need have little concern when 45 planning the mold as to location of the mold cavities so long as they are well within the dimensional limits of the mold.

As soon as the sprue opening in the mold is filled with 50 the molten material to be cast which obviously occurs in an extremely short time, the application of vacuum to the mold insures an "all-over" pull on the mold cavities with the result that residual air and gases in the cavities are withdrawn, and any gases that might be occluded in the molten material to be cast, as well, are withdrawn. Furthermore, the necessity for the provision of large shrink-heads in the top mold section is eliminated, and shrinkage upon cooling can be accommodated by relatively smaller shrink reservoirs located in the bottom mold section. Furthermore, the volume of the runners can be substantially 55 reduced. Thus, with the smaller shrink requirement and the smaller runner volume a substantially larger casting yield for the quantity of melt poured obtains.

Referring particularly to the form of the invention 60 shown in Fig. 11 of the drawings, wherein the molten material to be cast is supplied upwardly to the bottom mold section 26B to the runner 30B, thence to the cavities 28B by the action of atmospheric pressure as a result of evacuation of the interior of the mold, turbulence in the melt is substantially minimized, particularly as compared to that produced in the case of introduction of melt into a mold by direct pouring and under conventional casting methods.

The forms of the invention shown in Figs. 12-17, inclusive, comprise applications specially adapted for the

casting of ferrous metals which have an extremely high melting point as compared with aluminum, for example. Such materials include both alloy and carbon steels, which metals must be raised to 2500° F. and upwards before melting occurs.

In the embodiment shown in Figs. 12 and 13, a mold supporting frame 84 fabricated from suitable channel and angle members is provided including a horizontal, flat main support member 85. A mold 86 is suitably mounted on the support member 85 by means of a fluid pressure operated clamping arrangement 88. In this instance, the clamping arrangement 88 includes a cylinder 89 rigidly mounted in depending relation from the horizontal frame member 85 and a piston 90 reciprocable within the cylinder by pressure fluid alternately entering and leaving the cylinder through openings 91. A clamping frame including vertically disposed tie rods 92 and parallel upper and lower cross bars 94, 95, respectively, is rigidly connected at the lower cross bar 95 to a piston rod 96 extending downwardly from the piston and cylinder 89, 90. As will be seen, the tie rods 92 pass through suitable openings in the horizontal frame member 85 so that the upper cross bar 94 is spaced a distance above the member 85 sufficient to accommodate the mold 86 therebetween. In this way the clamping frame is adapted for up and down movement with respect to the mold 86 as the piston 90 reciprocably traverses the cylinder 89.

In carrying out the invention the mold 86, formed of suitable porous ceramic material, and the cavities 98 therein (Fig. 17) are subjected to an indirectly applied vacuum by means of an upwardly facing vacuum plate 99 disposed in mold supporting relation on the horizontal frame member 85. As will be seen, the mold 86 is securely gripped between the vacuum plate 99 and the upper cross bar 94 when the metal to be cast is ready for pouring.

Because the hereinbefore described plaster-type mold material undergoes spalling in the melting temperature range of carbon and alloy steels, e.g. 2500° F. and up, it is necessary to provide an investment material which has the requisite high temperature refractory qualities and yet is capable of being formed into a porous mold. One form of such an investment material comprises the following ingredients substantially in the indicated portions by weight:

	Percent
Powdered silica	40
Ethyl silicate	33
China clay	27

For use the above ingredients are mixed with water in an adequate amount to obtain the desired molding consistency. A characteristic of this molding material, however, is that after being mixed it must be heated to a temperature of about 2000° F. before setting up to permit handling.

Accordingly, provision is made for sustaining the form of the mold during curing thereof by completely encasing the investment material within a shell or sheath 100 which becomes a permanent part of the mold. With particular reference to Figs. 12 and 17, it will be seen that the illustrative shell 100 takes the form of an open end metal cylinder into which the investment material is poured after mixing and which serves to completely enclose the mold material during both curing thereof and subsequent casting therein of molten metal. Thus, an empty cylinder 100 may be placed on a suitable flat base (not shown) and filled with the formable wet investment material there being properly placed within the cylinder a suitable cavity forming material or pattern. Insertion of the filled cylinder in an oven (not shown) maintained at approximately 2000° F. for a suitable time to cure the mold material and to melt the cavity forming material if such was used then imparts a permanent set to the mold. The sheathed mold 86 is then in condition to be clamped

in position on the vacuum plate 99 for admission thereto of molten metal.

Interposed between the top of the mold 86 and the upper cross bar 94 is a top mold plate 101 having an opening 102 in registry with the mold sprue opening 104 whereby to direct the molten metal to be cast from a lip pour ladle or the like (not shown) into the mold.

Thus, the cavities 98 of the mold 86 are evacuated by subjecting the mold to a vacuum applied to the plate 99 through a suitable vacuum connection 105 communicating with a vacuum source (not shown). As before, the vacuum action withdraws air and other gases from the cavities 98 and also draws the molten material being cast against the cavity walls.

15 The vacuum plate 99 shown is very similar to the plates hereinbefore described, except that the plate shown in this embodiment is shaped as a circular disc to conform to the cylindrical mold shape. From Figs. 16 and 17, it is seen that the plate 99 is provided with a waffle-iron-like upper surface 106 so as to define a pattern of interconnected circular and straight passages 108 over substantially the entire surface of the mold. Communication between these inner passages 108 and the vacuum connection 105 is effected through an opening 109 provided in the back of the plate. In this way the waffle-iron-like formation provides plate feet 110 distributed over the entire bottom surface of the mold 86 so as to uniformly distribute the vacuum forces thereover.

20 For further assuring positive application of vacuum to the mold cavities 98 and for minimizing dissipation of the vacuum forces through leakage the vacuum plate 99 is provided with an upstanding circular knife edge 111 adapted to bite into the relatively soft lower surface of the mold 86. The knife edge 111 fits tightly into an appropriate groove provided in the plate so as to be easily replaced when dull. Thus, any inflow of air into the interconnected passages 108 must be by way of the porous walls of the mold 86.

25 A preferred form of the invention includes an array of closely spaced perforations 113 provided over substantially the entire surface of the mold shell 100 in order to permit air to be drawn therethrough and through the porous investment material to thereby create a chilling action on the castings within the mold. It is found that such an arrangement effects a higher rate of cooling of the castings than that normally attainable so as to produce a finely grained casting product having uniform and highly desirable physical characteristics.

30 The embodiment of the invention illustrated in Figs. 14 and 15 is similar to that shown in Figs. 12-13 except that the sheathed mold 86a is clamped to the angularly disposed outlet or mouth 114 of a rockable furnace 115, preferably of an electric type, which may be tilted to fill the mold with molten metal. Thus, as shown in the drawings, a frame 116 for supporting the tiltable furnace 115 is provided and suitable means including a gearmotor 118 and cradle member 119 are used for rocking the furnace between an upright and a tilted position (shown in phantom in Fig. 14).

35 The furnace 115 is pivotally supported on the frame 116 by arms 120 and the rocking cradle 119 is pivotally connected to the furnace at some point 121 above the axis of the supporting arms. Rotative motion is imparted to the cradle 119 and furnace 115 by means of a pinion 122 driven by the gearmotor 118 and adapted to engage a rack 124 formed in the lower portion of the cradle.

40 An upwardly extending frame formed of flat bars 125 is firmly fixed to the furnace supporting arms 120 so as to be swingable therewith and provision is made for tightly clamping the mold 86a to the furnace. Thus, a fluid cylinder 126 is rigidly connected to the upper frame bar 125 in depending relation thereto and a reciprocable piston 126 disposed in the cylinder carries a vacuum plate 99a on the lower end of a piston rod 129. The pressure fluid operated piston and cylinder arrangement 128, 126

accordingly moves the vacuum plate 99a toward or away from the furnace mouth 114, as desired, to clamp or release the mold 86a.

The mold 86a employed is identical to that used in the apparatus of Figs. 12 and 13, as shown in Figs. 16 and 17, having a sprue opening (not shown) positioned contiguous to the furnace mouth 114. A cylindrical shell 100a surrounds the investment material forming the mold, the shell being preferably formed with perforations 113a to facilitate cooling of the castings after the molten metal has been poured.

As will be observed, the ends of the mold 86a are appropriately sealed from leakage of air or molten metal. Thus, it is preferred to interpose a gasket 130 between one end of the mold and the furnace mouth 114. Likewise the other end of the mold is sealed by the provision on the operating surface of the vacuum plate of a circular raised knife edge adaptable to assume a biting relationship with the mold material.

Operation of the illustrative apparatus of Figs. 14 and 15 is effected by melting in the electric furnace 115 a metal charge to be cast. With the mold 86a clamped firmly to the furnace mouth 114 and when the metal is transformed into molten condition, the furnace 115 is rocked by means of the gearmotor 118 and cradle 119 from the upright to the tilted position. Vacuum may be applied to the vacuum plate 99a simultaneously with the flow of melt from the furnace 115 into the mold 86a, or the vacuum may be applied whenever desired.

The method and apparatus hereinbefore described have been placed in use under actual production conditions. Through the utilization thereof it has been found that not only does a substantially higher percentage of yield obtain, but additionally the castings so formed do in fact possess improved physical properties. Further, it has been found that there are substantially no rejects when the molds themselves are properly formed. Precision castings have been successfully made under production conditions and speeds with extremely thin-walled sections to a specification accuracy of .005 of an inch.

There is shown in Figs. 18-20 a modified form of clamping plate which may also be used in any of the illustrative casting apparatuses described herein. An illustrative vacuum clamping plate 150 is there shown which is similar in overall shape and construction to the clamping plates 24, 24B and 26A described above. As shown the plate 150 comprises the top plate for use in one of the illustrative casting apparatuses and is provided with a waffle-iron-like formation of feet or pads 152 distributed over its entire undersurface.

As before, the spaced feet 152 uniformly distribute clamping pressure over the surface of a porous upper mold section 154 of any of the types described heretofore and define therebetween a pattern of interconnected passages 156 over substantially the entire upper surface of the mold section. Evacuation of the mold cavities is accomplished by subjecting the interconnected passages 156 to a vacuum whereby air, occluded gases, and the like are withdrawn through the porous walls of the mold. As in the case of the vacuum clamping plates described above, the plate 150 is preferably provided about the periphery of its clamping surface with suitable knife edges 158 which are adapted to bite into the relatively soft upper surface of the mold and thereby minimize leakage or dissipation of vacuum.

The improvement disclosed here and shown in Figs. 18-20 of the drawings concerns the opening 160 which is provided in the plate 150 to provide communication between the interconnected passages 156 and a vacuum pump (not shown). In an arrangement similar to those disclosed above as concerns the vacuum plates 24, 24B, and 26A, connection between the plate opening 160 and the vacuum pump is accomplished using a suitable vacuum hose (not shown) which is secured to the plate by means of a screw-threaded fitting 162.

Before describing the modified vacuum plate 150 in detail reference should be made to some of the problems which are overcome by using the improved plate construction in a casting apparatus. It has been found in practice that the vacuum hose extending between the clamping plate 150 and the vacuum pump often becomes restricted or entirely obstructed with solid materials such that the vacuum action at the clamping plate is effectively shut off before all of the occluded gases and the like have been withdrawn from the mold cavities. That is, solid materials are drawn from the mold outwardly through the plate opening and into the vacuum line with the result that the latter becomes plugged and the effective application of vacuum to the mold is cut off.

These solid materials often comprise particles of the mold itself, such as granules of sand, gypsum, or other mold material which may be present in a loose state on the surface of the mold or may result from some crumbling of the soft mold material at its surface. Sometimes the sealing knife edges 158 around the periphery of the clamping plate tend to dislodge particles of mold material from the mold surface.

The most troublesome type of solid material which may clog the vacuum passages is the molten metal itself which is being cast. Occasionally a mold cavity is positioned very close (perhaps $\frac{1}{4}$ inch) to the outer surface of the mold such that a fine crack or void in the thin mold wall will permit the vacuum to break the wall. If this occurs, some of the molten metal being poured into the mold cavities is invariably drawn through the break in the mold wall and into the interconnected vacuum passages 156 defined by the plate clamping feet 152. Since the molten metal solidifies within the vacuum hose and often within the pump itself it is necessary to completely disassemble and clean the component parts of the pump, a laborious and time consuming task.

The use of conventional filtering means on the vacuum lines to protect the vacuum pump has been found to be ineffective since these very quickly become clogged with the molten metal or mold particles and thus cut off vacuum action. In any event such filters must be placed in the vacuum hose or line at some point between the clamping plate and the pump such that the portion of the vacuum line adjacent the clamping plate is still subject to plugging.

In carrying out that aspect of the invention shown in Figs. 18-20 of the drawings, the illustrative mold clamping plate 150 is provided with means surrounding the vacuum opening 160 for preventing passage of any solid materials into the vacuum hose or pump while yet assuring free passage of gases through the opening 160 so that occluded gases within the mold cavities may be quickly and completely removed therethrough. In this instance the means comprises an approximately square pad 166 integral with the plate 150 and surrounding the plate opening 160 and defined by certain of the interconnected passages 156, and a porous disc 168 covering the plate opening 160 and shouldered within the pad 166 such that it is interposed between the plate and the mold surface 154 (see Fig. 20) during casting.

As will be seen from Fig. 18 which shows the plate 150 without the porous disc 168 in place, the pad 166 comprises a plurality of mold engaging feet 170 which cover substantially the entire area of the pad except for the center thereof through which the plate opening 160 passes. The mold engaging feet 170 are defined by a plurality of pad grooves 172 which extend radially outwardly over the mold engaging surface of the pad from the central plate opening 160 and thereby provide communication between the interconnected passages 156 and the opening 160.

A counterbore 173 somewhat larger than the diameter of the plate opening 160 is provided in the center of the pad 166 in order to provide a shoulder 174 for reception of the porous disc 168 which is preferably of flat cylin-

drical shape. As will be seen from Fig. 20 the depth of the counterbore 173 from the surface of the mold engaging pad feet 170 is the same as the thickness of the disc 168 such that when the plate 150 is in place against the surface of the mold 154 the disc 168 is maintained firmly against the mold surface. It will be noted that the counterbore 173 is slightly tapered inwardly to facilitate entry of the disc 168 therein and removal therefrom. The disc 168 is thus a wedge fit when in place within the counterbore 173.

Various materials of construction may be used for the disc or wafer 168 so long as the resulting material is porous and resistant to whatever high temperature conditions are encountered with the particular metals to be cast. One satisfactory such disc is formed as a refractory material by mixing a small amount of a suitable binder, such as the resin binder manufactured and sold by the Acme Resin Corporation of Forest Park, Illinois and designated by them as their No. 760 resin, with a suitable coarse grade sand, forming the mixture into the disc shape in a conventional core box, and then baking the shaped disc at about 800° F. for an hour or more. The resulting disc is hard, porous due to elimination of resin components during baking, and resistant to most temperatures encountered in the casting of metal shapes. Of course other binders can be used as well, and indeed the disc material may be formed of other high temperature resistant materials, such for example as a suitable sintered metal which has the desired heat resistant qualities.

The modified plate shown in Figs. 18-20 has many advantages. The flat disc 168 is, as noted above, held firmly between the plate opening 160 and the mold surface 154 when the entire casting apparatus is assembled and the metal is being cast. As will be clearly seen from Fig. 20, any solid materials such as mold particles of molten metal which enter the interconnected passages 156 from the mold will be drawn along those passages to the plate pad 166 and thence through the pad grooves 172 until the particles engage the outer peripheral edge surface of the disc 168. The solid particles are stopped at this point and must remain lodged against the outer edge surface of the disc.

An important feature of this aspect of the invention is that the flat disc 168 in this condition provides a broad filtering area in engagement with the mold surface 154 such that effective vacuum action is exerted upon the inner mold cavities over the entire flat area of the disc. Because of the substantial area of flat engagement between the disc 168 and the mold 154, that portion of the mold in contact with the disc is strengthened against any cracking or breaking of the mold wall over that area. Since the mold wall remains intact over the area of engagement with the disc 168, and because any loose solid particles from the mold are retained on the edge surface of the disc, there is no substantial impairment of the vacuum action being exerted through the flat disc surface upon the mold cavities. Even in an extreme hypothetical situation in which all of the pad grooves 172 might become clogged with solid materials, vacuum would still be drawn through the flat surface of the disc 168 engaging the mold surface.

Another feature of this modified form of the invention concerns the ease with which the filtering means may be cleaned in between successive uses of the casting apparatus. Upon separation of the clamping plate 150 from the casting apparatus and discontinuation of vacuum action, the disc 168 drops easily out of the plate shoulder 174 and the solid particles may be easily brushed away from the disc as well as from the grooves 172 and other plate passages. Reassembly is accomplished readily by applying vacuum to the clamping plate 150, placing the disc 168 within the plate shoulder 174 so that it is drawn into a wedge fit therein and held firmly by the vacuum action, and reclamping the casting plates of the apparatus into place surrounding a new mold. The

porous disc 168 thus permits passage of air therethrough while yet providing enough resistance to air flow to enable it to be held in place within the plate under impetus of the vacuum.

In the preferred form of the modified plate there are yet other advantageous features. Attention is drawn to the difference in depth between the pad grooves 172 and the adjacent interconnected plate passages 156. It will be observed that the grooves 172 are preferably considerably more shallow than (only about one-third as deep in this case) the passages 156. These shallow grooves 172 communicating between the passages 156 and the porous disc 168 function in what might be termed a "coarse" filtering action as compared with the relatively "fine" filtering action through the disc 168. This is best understood upon a consideration of the mechanics of the path of flow should molten metal or mold particles be drawn into the interconnected vacuum passages 156. Goblets or particles of such molten metal are first drawn along the relatively large and deep passages 156 toward the plate pad 166. Upon reaching the pad grooves 172 which have a substantially reduced cross sectional area as compared with the passages 156, some large metal goblets may be retained at the entrance to the grooves 172 or may be broken up into smaller particles. To prevent complete stoppage of particles at these points the pad 166 is provided with sloping transition surfaces 175 extending over the difference in depth between the passages 156 and the grooves 172.

At this point of entry of the molten metal particles into the grooves 172 the velocity of the flow of gases and the like from the mold cavities increases substantially in accordance with the above-mentioned change in cross-sectional area of the path of gas flow such that a chilling action takes place tending to solidify the particles of molten metal. As a result many times the chilled metal particles, or the smaller particles of mold material, are caught within the confines of the narrow grooves 172 so that they never reach the porous disc 168. Of course much of the particulate material will traverse the pad grooves 172 and be drawn up against the edge surfaces of the disc 168 as described above. Since the cross-sectional area of the grooves 172 is invariably considerably greater than the size of the voids in porous disc 168 the narrow grooves provide what might be termed a "coarse" filtering or screening action.

It is found in practice that this arrangement not only prevents the vacuum line from plugging up but assures the maintenance of a positive vacuum against the surface of the mold for a sufficient period of time to permit the occluded gases to be withdrawn from the mold cavity. Thus, while there is still the possibility that even the disc 168 could become clogged still this would not occur until a sufficient length of time had passed so that the application of vacuum would have served its purpose, i.e. the casting operation would be complete.

While the modified form of the invention disclosed in Figs. 18-20 of the drawings has been described as applied to the top plate of a casting apparatus and a plate of rectangular form, the invention is in no wise so limited. Any suitable shape casting plate may be employed and it may be a bottom plate or the like as well as the top plate. Similarly the plate pad 166 need not be square-shaped but may take any suitable form and the disc 168 need not be cylindrically shaped but may be formed as a rectangular or square solid or in any other feasible shape.

Likewise this aspect of the invention may be used in permanent molds such as cast iron or the like used for casting various alloys and aluminum as well as non-permanent types. In this application a vacuum opening is provided on the inner wall of the permanent mold, with a suitable recess surrounding the opening; the mold comprising for example a heavy walled cast iron cylinder about 10 inches in diameter and perhaps 6 inches deep,

and the recess being sized and shaped to receive therein a porous disc of suitable contour and of the character described above. The position of the disc within the mold is such that it engages the portion of the casting to be poured which has a plaster core therein so that a vacuum may be drawn from the molten metal through the plaster core and thence through the porous disc which protects the vacuum line from becoming plugged with metal particles or the like.

The present application is a continuation-in-part of my copending application Serial No. 561,310 filed January 25, 1956, now abandoned, which is in turn a continuation of my now abandoned application Serial No. 379,210 filed September 9, 1953.

I claim as my invention:

1. A casting apparatus comprising, in combination, a mold formed of porous material defining a cavity for the reception of the material to be cast, a plate having a plurality of interconnected passages formed in one face thereof and defining a plurality of spaced feet engageable with said mold, said mold and said plate defining spaced passages therebetween, said plate having an opening therein adapted for connection with evacuating means and including on said face thereof a pad surrounding said opening and having a depth substantially the same as the depth of said spaced passages, a counterbore on said plate face within said pad and surrounding said plate opening, said pad having grooves therein communicating between said spaced passages and said plate opening and dividing said pad into a plurality of feet for engagement with the juxtaposed mold surface, means for applying a vacuum to said plate through said plate opening whereby vacuum is transmitted through said spaced passages to the exterior surface of the mold and indirectly to said mold cavity through the mold walls defining the same for effecting removal of gases from the mold cavity, said pad grooves having a depth substantially less than the depth of said spaced passages whereby flow of gases from said mold cavity to said plate opening is restricted, and a porous disc within said counterbore disposed in parallel relationship to the interface between said plate and said mold and being of a sufficient thickness to locate the outer surface of the disc in coplanar relationship with the mold bearing surface of said spaced feet so that the disc is held in firm engagement with the contiguous area of the mold surface whereby the disc permits passage therethrough of gases being evacuated from the mold cavity but positively prevents passage into the plate opening of any solid particles that might otherwise obstruct said opening.

2. A casting apparatus comprising, in combination, a mold formed of porous material defining a cavity for the reception of the material to be cast, a plate having a plurality of interconnected passages formed in one face thereof and defining a plurality of spaced feet engageable with said mold, said mold and said plate defining spaced passages therebetween, said plate having an opening therein adapted for connection with evacuating means and including on said face thereof a pad surrounding said opening and having a depth substantially the same as the depth of said spaced passages, a counterbore on said plate face within said pad and surrounding said plate opening, said pad having grooves therein communicating between said spaced passages and said plate opening and dividing said pad into a plurality of feet for engagement with the juxtaposed mold surface, means for applying a vacuum to said plate through said plate opening whereby vacuum is transmitted through said spaced passages to the exterior surface of the mold and indirectly to said mold cavity through the mold walls defining the same for effecting removal of gases from the mold cavity, said pad grooves extending radially outward from said plate opening and having a narrow depth as compared with the depth of said passages whereby flow of gases from said mold cavity to said plate opening is restricted, and a

porous disc within said counterbore disposed in parallel relationship to the interface between said plate and said mold and being of a sufficient thickness to locate the outer surface of the disc in coplanar relationship with the mold bearing surface of said spaced feet so that the disc is held in firm engagement with the contiguous area of the mold surface whereby the disc permits passage therethrough of gases being evacuated from the mold cavity but positively prevents passage into the plate opening of any solid

10 particles that might otherwise obstruct said opening.

3. A casting apparatus comprising, in combination, a mold formed of porous material defining a cavity for the reception of the material to be cast, a plate having a plurality of interconnected passages formed in one face 15 thereof and defining a plurality of spaced feet engageable with said mold, said mold and said plate defining spaced passages therebetween, said plate having an opening therein adapted for connection with evacuating means and including on said face thereof a pad surrounding said 20 opening and having a depth substantially the same as the depth of said spaced passages, a counterbore on said plate face within said pad and surrounding said plate opening, said pad having grooves therein communicating between said spaced passages and said plate opening and dividing 25 said pad into a plurality of feet for engagement with the juxtaposed mold surface, means for applying a vacuum to said plate through said plate opening whereby vacuum is transmitted through said spaced passages to the exterior surface of the mold and indirectly to said mold cavity 30 through the mold walls defining the same for effecting removal of gases from the mold cavity, and a porous disc within said counterbore disposed in parallel relationship to the interface between said plate and said mold and being of a sufficient thickness to locate the outer surface 35 of the disc in coplanar relationship with the mold bearing surface of said spaced feet so that the disc is held in firm engagement with the contiguous area of the mold surface whereby the disc permits passage therethrough of gases being evacuated from the mold cavity but positively prevents 40 passage into the plate opening of any solid particles that might otherwise obstruct said opening, said pad grooves terminating adjacent said plate opening against the peripheral edge surfaces of said porous disc so that any solid particles accumulate along these edge surfaces 45 whereby the flat surface of the disc lying in the plane of the mold surface remains free and unobstructed to passage of gases therethrough.

4. A casting apparatus comprising, in combination, a mold formed of porous material defining a cavity for the 50 reception of the material to be cast, a plate having a plurality of interconnected passages formed in one face thereof and defining a plurality of spaced feet engageable with said mold, said mold and said plate defining spaced 55 passages therebetween, said plate having an opening therein adapted for connection with evacuating means and including on said face thereof a pad surrounding said opening and having a depth substantially the same as the depth of said spaced passages, a counterbore on said plate face within said pad and surrounding said plate 60 opening, said pad having grooves therein communicating between said spaced passages and said plate opening and dividing said pad into a plurality of feet for engagement with the juxtaposed mold surface, means for applying a vacuum to said plate through said plate opening whereby 65 vacuum is transmitted through said spaced passages to the exterior surface of the mold and indirectly to said mold cavity through the mold walls defining the same for effecting removal of gases from the mold cavity, said pad grooves having a depth substantially less than the depth 70 of said spaced passages whereby flow of gases from said mold cavity to said plate opening is restricted, and a porous disc within said counterbore disposed in parallel relationship to the interface between said plate and said mold and being of a sufficient thickness to locate the outer surface of the disc in coplanar relationship with the

mold bearing surface of said spaced feet so that the disc is held in firm engagement with the contiguous area of the mold surface whereby the disc permits passage therethrough of gases being evacuated from the mold cavity but positively prevents passage into the plate opening of any solid particles that might otherwise obstruct said opening, said pad grooves terminating adjacent said plate opening against the peripheral edge surfaces of said porous disc so that any solid particles accumulate along these edge surfaces whereby the flat surface of the disc lying in the plane of the mold surface remains free and unobstructed to passage of gases therethrough.

5. A casting apparatus comprising, in combination, a mold formed of porous material defining a cavity for the reception of the material to be cast, a support for the mold, a plate having a plurality of interconnected passages formed in one face thereof and defining a plurality of spaced feet engageable with said mold opposite said support, means for clamping said plate against said mold, said mold and said plate defining spaced passages therebetween, a perforated member entirely surrounding the exposed mold portions for sustaining the form thereof and permitting passage of air therethrough, said plate having an opening therein adapted for connection with evacuating means and including on said face thereof a pad surrounding said opening and having a depth substantially the same as the depth of said spaced passages, a counterbore on said plate face within said pad and surrounding said plate opening, said pad having grooves therein communicating between said spaced passages and said plate opening and dividing said pad into a plurality of feet for engagement with the juxtaposed mold surface, means for

applying a vacuum to said plate through said plate opening whereby vacuum is transmitted through said spaced passages to the exterior surface of the mold and indirectly to said mold cavity through the mold walls defining the same for effecting removal of gases from the mold cavity and for drawing air into the mold through said perforated mold supporting member, said pad grooves having a depth substantially less than the depth of said spaced passages whereby flow of gases from said mold cavity to said plate opening is restricted, and a porous disc within said counterbore disposed in parallel relationship to the interface between said plate and said mold and being of a sufficient thickness to locate the outer surface of the disc in coplanar relationship with the mold bearing surface of said spaced feet so that the disc is held in firm engagement with the contiguous area of the mold surface whereby the disc permits passage therethrough of gases being evacuated from the mold cavity but positively prevents passage into the plate opening of any solid particles that might otherwise obstruct said opening.
